Des. 238,639

Patented Feb. 3, 1976

238,639

COMBINED MIRROR AND SHELF

John W. Johnson, 626 E. Gutierrez St.,
Santa Barbara, Calif. 93101

Filed Dec. 9, 1974, Ser. No. 530,764

Term of patent 14 years

Int. Cl. D6—04

U.S. Cl. D6—132

Fig. 1

Fig. 2

FIG. 1 is a front elevational view of a combined mirror and shelf showing my new design, the rear and top of the shelf are flat and unornamented.

FIG. 2 is a side elevational view thereof.

I claim:

The ornamental design for a combined mirror and shelf, substantially as shown.
